UNITED STATES PATENT OFFICE.

HARRY BLAKE, OF CHICAGO, ILLINOIS, ASSIGNOR TO HIMSELF AND C. E. BLAKE, OF SAME PLACE.

MOTIVE POWER.

SPECIFICATION forming part of Letters Patent No. 283,063, dated August 14, 1883.

Application filed February 5, 1883. (No model.)

To all whom it may concern:

Be it known that I, HARRY BLAKE, of Chicago, in the county of Cook and State of Illinois, have invented new and useful Improvements in Motive Powers, of which the following is a specification, reference being had to the accompanying drawings, illustrating the invention, in which—

Figure 1 is a longitudinal sectional elevation of a motive power as applied to a hand-car embodying my invention; Fig. 2, a top or plan view thereof; Fig. 3, detached parts removed from the complete structure.

The object of the present invention is so to improve the mechanism for driving the wheels of the ordinary hand-car that there shall be the least possible friction, lost motion, or liability to get out of order, and at the same time to apply the power equally to both trucks in a manner best adapted to the application of human strength. The power is also designed for driving other mechanisms; and it may be said that it is an improvement on or an advance on the motive power patented to W. W.

Corey on November 28, 1876, No. 184,761.

The nature of the invention consists in an inverted T-lever, which at either side actuates two connecting-rods and two levers; also, a pitman-rod. The pitman-rod, at either side of the T-lever, respectively actuates a crank-shaft on which is fixed a gear-wheel which meshes into a pinion on the axle, and consequently when the T-lever has given to it an oscillating movement the wheels are rotated, as the whole is hereinafter fully described and shown.

A' represent the frame, and B the wheels, of an ordinary hand-car, and C C is the frame which supports the shaft of the T-lever J. To the arms H H, respectively, of this lever is pivoted a connecting-rod, l, whose lower end is pivoted to a lever, F, at d, which, at a, is pivoted to a stud, E, attached to the frame-piece A'. To the middle portion of the lever F is pivoted a connecting-rod, L, whose lower end, at M', is pivoted to a bent lever, G. This last-mentioned lever is journaled to the side

frame, A, at b b, and its upper end is pivoted at f to the outer end of a pitman, K K. The inner end of the pitman is journaled to a crank-shaft, M, to which is attached a cog-gear, D, 50 which meshes into a pinion, E', on the car-axle W.

By an inspection of the drawings it will be seen that the mechanism connected with one arm, H, of the T-lever is an exact reverse 55 counterpart of the mechanism connected with the other arm, even to the cog-gear, being on opposite sides of the car. The connecting-rods L l are single pieces each of metal, but the lever F is formed of two pieces, and the 60 bent lever G operates between them. The pitmen K K are double, the bars of which are farther apart at their outer ends than where they are journaled to the crank-shaft M, whereby one pitman may work inside of the other 65 in the position shown at Fig. 2. The lever J is pivoted to the frame C C by means of a shaft, e, so as to have an oscillating motion longitudinally with the car.

Where a greater motion is to be given to the 70 axles W, the dimensions of the wheels D E' may be changed, and where a greater or less power be required the arms H and levers G L may have given to them different proportions 75 with reference to their fulcrums and to where the power is applied.

In the foregoing one application of my improvement has been given, and from it a person skilled in the art will readily put it to other uses to which it may be adapted.

I claim and desire to secure by Letters Patent—

In motive powers, the T-lever J, levers F G, connecting-rods L l, in combination with the double pitman-rods K K, (operating independently to produce a unity of motion,) the crank-shafts M, and gear-wheels D E, substantially 85 as and for the purpose specified.

HARRY BLAKE.
